(57) CLAIM

The ornamental design for a universal mounting template, as shown and described.

DESCRIPTION

FIG. 1 is a perspective view of a universal mounting template showing my new design;

FIG. 2 is a top plan view thereof;

FIG. 3 is a bottom plan view thereof; and,

FIG. 4 is a side edge view thereof.

The broken lines showing of texts and numbers in FIGS. 1-2 are for illustrative purposes only and form no part of the claimed design.
